UNITED STATES PATENT OFFICE.

KATHLEEN M. POLHAMUS, OF SOUTH PASADENA, CALIFORNIA.

DESIGN FOR A SUNBONNET.

59,033.

Specification for Design. Patented Sept. 13, 1921.

Application filed May 11, 1921. Serial No. 468,751. Term of patent 3½ years.

To all whom it may concern:

Be it known that I, KATHLEEN M. POLHAMUS, a citizen of the United States, residing at South Pasadena, in the county of Los Angeles and State of California, have invented a new, original, and ornamental Design for a Sunbonnet, of which the following is a specification, reference being had to the accompanying drawing, forming a part thereof.

Figure 1 is a front view of a sunbonnet showing my new design, and

Fig. 2 is a rear view thereof.

I claim:

The ornamental design for a sunbonnet as shown.

KATHLEEN M. POLHAMUS.
